DESIGN FOR A BOTTLE

Ruth M. Clark, Albany, N. Y., assignor to Norman
A. Henderson, Albany, N. Y.

Application March 9, 1942, Serial No. 106,120

Term of patent 14 years

To all whom it may concern:

Be it known that I, Ruth M. Clark, a citizen of the United States, residing at Albany, county of Albany and State of New York, have invented a new, original, and ornamental Design for a Bottle, of which the following is a specification, reference being had to the accompanying drawing, forming a part thereof, in which—

Fig. 1 is a perspective view of a bottle showing my new design;

Fig. 2 is a fragmentary sectional view on line 2—2 of Fig. 1; and
Fig. 3 is a fragmentary sectional view on line 3—3 of Fig. 1.

I claim:
The ornamental design for a bottle, as shown.

RUTH M. CLARK.
